(57) **CLAIM**

The ornamental design for a bucket filter, as shown and described.

DESCRIPTION

FIG. 1 is a top perspective view of a bucket filter showing our new design;

FIG. 2 is a front elevation thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is bottom perspective view thereof.

The broken lines shown in the figures are for the purpose of illustrating portions of the bucket filter and form no part of the claimed design.

1 Claim, 6 Drawing Sheets
